MACHINE FOR STRINGING TAGS.

No. 883,223.

Specification of Letters Patent. Patented March 31, 1908.

Application filed June 6, 1907. Serial No. 377,582.

To all whom it may concern:

Be it known that I, LAWRENCE A. MCGRATH, a citizen of the United States; and a resident of Randolph, in the county of Norfolk and State of Massachusetts, have invented an Improvement in Machines for Stringing Tags, of which the following description, in connection with the accompanying drawing, is a specification, like letters on the drawing representing like parts.

This invention relates to machines for stringing tags and has for its object to provide a novel machine of this class by means of which tags may be quickly and accurately strung.

Machines have heretofore been devised for stringing tags by looping a string through the eye of the tag, but so far as I am aware, all such machines have employed a straight threading device for inserting the string through the eye of the tag. Where a threader of this type is used, it is necessary to employ special mechanism for carrying either the looped end of the string or the free end thereof around the end or edge of the tag in order to effect the drawing of the ends through the loop of the tag.

One of the features of my invention is to provide a novel form of threader which operates both to insert the string through the eye of the tag and also to carry the loop of the string around the end or edge of the tag and in position to have the ends of the string drawn through the loop thereof. By making the threader capable of performing both these operations, the mechanism may be simplified and the speed of operation increased.

Another feature of my invention relates to the manner of handling the string. In accordance with my invention I have provided means for controlling the length of string to be inserted in the tag throughout its entire extent while presenting the string to the threader and while it is being drawn through the eye of the tag. By means of this construction wherein the string is thus controlled, it is possible to accurately and positively present a length of string to the threader for each cycle of operations.

I will first describe one embodiment of my invention and then point out the novel features thereof in the appended claims.

In the drawings wherein I have illustrated one embodiment of my invention, Figure 1

is a front side elevation thereof; Fig. 2 is a section on substantially the line $b-b$, Fig. 11; Fig. 3 is a detail of the device for removing the strung tags; Fig. 4 is a rear side elevation of the machine shown in Fig. 1; Fig. 5 is a detail of the positioning means for the string presenter; Fig. 6 is a plan view of the machine shown in Fig. 1; Fig. 7 is a perspective view in detail of the string presenter; Fig. 8 is a similar view of the cutters for cutting the string, said view showing the means for holding the end of the string from which the severed length has been cut; Fig. 9 is a detail of the threader and loop remover; Fig. 10 is a section on the line $x-x$, Fig. 1, looking toward the right; Fig. 11 is a section on substantially the line $y-y$, Fig. 1; Fig. 12 is a plan view of the knotter; Fig. 13 is a side view of the knotter; Fig. 14 is a section on the line $c-c$, Fig. 10; Fig. 15 is a section on the line $d-d$, Fig. 10; Fig. 16 is a section on the line $e-e$, Fig. 15; Figs. 17 and 18 are details of the threader; Fig. 19 is a section on the line $a-a$, Fig. 1, looking toward the right; Fig. 20 is a detail of the threader and loop remover; Fig. 21 is a detail of the support for the tag; Figs. 22 to 26 are views illustrating the various steps in the operation of the machine, each of said views showing both the threader, loop remover and knotter in various positions, and also the tag and the string in different positions corresponding to the position of the threader and knotter; Figs. 27 and 28 are views showing the operation of the knotter. Fig. 29 is a view showing a tension device.

The machine herein shown is of that class which loops the string through the eye of the tag and then draws the ends of the string through the loop thereof, and the device as illustrated comprises as its operative elements a threader constructed to take a severed length of string, loop the same through the eye of the tag and carry the looped end thereof around the end or edge of the tag; a loop remover to remove the looped end of the string from the threader; and a knotter to grasp the free ends of the string and draw them through the loop; thus completing the stringing operation. In addition to these features, the machine herein shown includes a string-feeding device which comprises a string presenter to present the string to the threader, a cutting device to cut the required length of string for each tag, and means to

hold the string and keep the entire portion thereof under control while it is being presented to the tag. The machine also has associated therewith suitable means for feeding the tags singly to the machine, supporting each tag in proper position while it is being strung and removing the strung tags from the machine. All these operative parts are shown as mounted on a suitable frame 3 and they derive their motion from a driving shaft 4 which is journaled on said frame and is driven from a pulley 5 in any suitable or approved way.

Each tag as it is being strung is supported on a tag support 6 and the tag is held in vertical position by a positioning device 7 which is shaped to receive the end of the tag, as clearly shown in Fig. 14. The means for feeding the tags singly to this holder and for discharging them therefrom after having been strung, will be more fully described hereinafter.

I will now describe the string-feeding device. This comprises in the present embodiment a rotatable member 8 carrying a plurality of radially-extending arms 9 and 10. The arms 9 constitute string-presenters for presenting the string to the thresher, and the arms 10 have mounted thereon cutters 15 for cutting the string into proper lengths, and holders or grippers for holding the string; all as will be more fully hereinafter described.

The string-presenting arms 9 are constructed as shown best in Fig. 7. Each has two string-carrying fingers 11, each provided with an open eye 12 in which the string 13 is adapted to be received; and associated with each finger 11 is a tension device 14 comprising two resilient members between which the string is frictionally held. Each arm 10 has mounted thereon the cutter 15 which is pivoted to the arm, as at 16, and which works against a cutting bed 17 formed on the arm. Each cutter is provided with a tail 18, see Figs. 6 and 8, which at the proper time is engaged by a cam 19 whereby the cutter is closed against the cutting bed to sever the string as will be more fully described hereinafter.

180 is a spring acting against the arm 12 and tending to keep the cutter opened away from the bed 17, as shown in Fig. 8. Each arm also carries the spring-pressed gripping jaw 20 which is shown as pivoted on the pivotal pin 16 and which is acted upon by a suitable spring 21 that tends to hold the jaw against the cutting bed 17. These arms 9 and 10 are arranged alternately on the member 8, as plainly seen in Figs. 1 and 4. The member 8 is mounted to rotate and also to move toward and from the tag holder or support 7, and to accomplish this I have shown said member as loosely mounted on a pivotal shaft 25 which has bearing blocks 250 thereon that slide back and forth in ways

28 formed on the portion 27 of the frame, see Figs. 4 and 11. The shaft is given its sliding movement in the ways 28 by means of two slotted arms 29 which are mounted on the rock-shaft 30, the slots of which arms embrace the ends of the shaft 25. The rock-shaft 30 is operated from the main shaft 4 by means of a cam 31 having a cam groove which engages a stud 32 projecting from one of the arms 29, as plainly seen in Figs. 6 and 11. The cam groove in the cam 30 is of such a shape as to rock the arms 29 backward and forward in proper time to accomplish the desired results, as will be more fully herein-after described; and such rocking movement of the arms reciprocates the shaft 25 in the ways 28 as will be obvious.

The rotary movement of the member 8 is intermittent, each step forward thereof bringing one of the string-presenting arms in the position shown in the drawings to present a string to the thresher. This intermittent rotary movement is secured by forming on the member 8 ratchet teeth 22 which are adapted to be acted upon by a pawl 23 carried by a gear segment 24 that meshes with a fixed rack 26 carried by the portion 27 of the frame. As the shaft 25 is reciprocated in the ways 28 the segmental gear 24 will be oscillated because of its engagement with the rack 26, and during the backward movement of said shaft or its movement toward the left Fig. 1, the rocking or oscillating movement of the pawl carrier 25 will cause the pawl to click over one of the ratchet teeth 22, and during the forward movement of said shaft said pawl will engage said ratchet tooth and cause the member 8 to rotate until the pawl carrier 24 is carried free from the end of the rack 26, as seen in Fig. 2. The length of the rack 26 and the disposition of the ratchet teeth 22 is such that when during the forward movement of the arms 29 the teeth of the pawl-carrier 24 have been carried out from engagement with the rack 26 one of the thread-presenting arms 9 stands in line with the eye of the tag, and during the remainder of the forward movement of the arms 29 said member 8 remains in this position with the string-presenting arm 9 directed toward the tag.

The string 13 surrounds the arms 9 and 10, as seen in Figs. 1 and 4, and said string is held by the gripping jaws 20 and also by the tension members 14. The string may be fed from any string mass which will be situated below the frame of the machine, and as the member 8 rotates and reciprocates, as above described, the string will be automatically picked up by the tension members and grippers on the ends of the arms, and by these tension members and grippers carried over to the tag by the rotary movement of said member 8. If desired a tension device 33 may be employed through which the

string passes on its way to the feeding member 8.

The operation of the feeding device may be briefly described as follows:—During the backward movement of the arms 29, the pawl carrier 24 is turned to bring the pawl into engagement with the next tooth 22, and during the first portion of the forward movement of said arms 29 the member 8 is rotated 10 to bring the next succeeding string-presenting arm 9 into operative position, and during the latter portion of said forward movement said string-presenting arm remains in this position, as shown in Fig. 1, and advances 15 toward the tag and into position to deliver the string to the threader. During this latter portion of the movement of the arm the tail 18 of the cutter carried by the arm 10 occupying the position *m* Figs. 1 and 4 engages 20 the cam 19 thereby causing the cutter to sever the string at this point, the end of the string from which the length has been cut being held by the gripping jaw 20 on said arm 10 and the length of the string which is 25 cut being that which spans the distance between the arm 10 occupying the position *n* Fig. 1, and that occupying the position *m* in said figure. The severed length of string is designated 34, and one end thereof is positively held by the gripping jaw 20 carried by 30 the arm 10 occupying the position *n*.

During the latter part of the forward movement of the member 8, the arm 9 carrying the severed length 34 of string is held in 35 its proper position by a positioning device in the form of a pin or stud 35 which is carried by the post 36, and which enters an opening formed in a lug 37 carried by the arm 9, as plainly seen in Fig. 5. During the forward 40 movement of the member 8, the end of the portion 34 of the string has been held by the gripping jaw 20 on the arm 10 which occupied the position *n*, Fig. 1, as above described; and when said carrier has nearly 45 completed its forward movement the tail of the jaw 20 on said arm engages a cam surface 38 carried by the post 36 and moves said jaw to release the end of the string. This releasing of the end of the portion 34 of 50 the string occurs substantially simultaneously with the cutting of the length 34 from the body of the string so that when the carrier 8 completes its forward movement both ends of the severed length 34 are free. During 55 the final forward movement of the string-presenting arm 9 with the severed length of string 34 carried thereby, the portion of the string which is situated between the two fingers 11 is carried over the end of and into engagement with the threader 39, and during 60 the first part of the backward movement of said member 8 the threader draws the string from the arm 9 and carries the loop of string through the eye of the tag as will be presently described.

The tension devices 14 keep the severed length of string 34 under tension while it is being drawn from the string-presenting device by the threader, as will be obvious. From the above it will be seen that the 70 length 34 of string which is to be threaded through the eye of the tag is under complete control throughout its entire extent while it is being fed to the threader, and that the tension devices 14 operate to control said length of string while the threader is inserting it in the eye of the tag. The string is thus positively presented to the threader and the grippers 20 together with the tension devices 14 hold the string taut and under perfect control until the threader has inserted the same 80 in the eye of the tag.

In order to prevent the member 8 from over-running as it is intermittently rotated, I may use some suitable friction device for 85 bringing it to rest as soon as the pawl-carrier 24 has left the rack 26, as shown in Fig. 2. Any suitable friction device may be employed for this purpose, and I have herein shown simply a screw 140 which is mounted 90 in one of the bearing blocks 250 and which bears against the hub of the member 8.

As stated above the threader, which is designated 39, is arranged to loop the string through the eye of the tag and carry the 95 looped end around the end or edge of the tag, and to accomplish this result I have in this embodiment of my invention made said threader on a curve which is substantially that of the arc of a circle, so that all points of 100 the threader are substantially the same distance from the center of the curve. This circular or partly circular shape of the threader is plainly seen in Figs. 22 to 25. Said threader is arranged to be rotated or 105 turned about the center of the curve thereof and in its rotating or turning movement, the end thereof passes through the eye of the tag being strung. The threader is provided at 110 its end with a string-engaging portion shown in the form of a notch 40, and as the threader turns, the notch engages the string and carries a loop thereof through the hole or eye in the tag. Owing to the circular shape of the 115 threader, the loop of the string is not only carried through the eye of the tag, but is also carried around the edge of the tag, as will be more fully hereinafter described. I prefer also to give my threader a helical shape and when it has said shape it turns about the 120 axis of the helical curve thereof.

In the present embodiment of my invention this threader is shown as supported directly on a post 60 rising from an arm 43 which extends from a hub 44 that rotates 125 about a fixed vertical shaft 45 carried by the frame, and the hub derives its rotation from a gear 46 loosely mounted on the shaft 45 and meshing with a rack 47 carried by a swinging arm 48 that is pivoted to the frame, 130

as at 49, and is provided with a projection 50 carrying a roll that engages a groove in a cam 51 mounted on the shaft 4. As stated above, the threadder 39 is formed on the arc of 5 a circle, and as it is rotated the notched end thereof passes through the hole in the tag 42. The movement given to the threadder is sufficient to carry the notched end thereof around 10 the edge of the tag and onto the same side thereof as that from which the threadder was inserted into the tag.

The threadder is made with a helical shape, 15 shown in Figs. 17 and 18, and as it turns to carry the string through the hole in the tag it is elevated to maintain the portion thereof passing through the hole always in the correct vertical position. This elevating movement of the threadder is secured by arranging the hub 44 to slide vertically on the 20 shaft 45 as well as to turn thereon, and by providing said hub with a cam groove 54 which has engagement with a fixed projection 55, herein shown as carried by the supports 56 for the table 6, see Fig. 10. The 25 cam groove 54 has the same pitch as the helical shape of the threadder. To permit the hub to slide on the shaft 45 without being disengaged from the gear 46, said gear is provided with a pin 52 which is slidably received in a recess 43 formed in the hub. 30 This construction locks the hub to the gear for rotary movement but permits the hub to move vertically with reference to the gear.

In order to clearly understand the operation 35 of stringing the tag I will refer now to Figs. 22 to 26 inclusive which show the various steps in performing this operation. In said figures I have associated with the elements of the machine perspective views of 40 the tag and the string in different positions. The string is first looped and presented to the tag 42, as shown in Fig. 22, and then said looped end is threaded through the hole 550 of the tag and passed around the end of the 45 tag, as seen in Fig. 23. The loop is then held, as seen in Fig. 24, and the ends of the string are passed through the loop, as seen in Fig. 25, and tightened, as seen in Fig. 26. These 50 various operations are performed by the threadder, the loop remover and the knotter, respectively, as will be now described. In Fig. 22 the end of the tag is shown in the holder 7, the threadder 39 is in its normal position and the string-presenting fingers 11 55 have presented a string to the notch 40 of the threadder and are being retracted, as shown by the arrow. Said figure also shows in perspective the relative position of the tag and string at this point in the cycle of operations. 60 The threadder then turns into the position shown in Fig. 23, and in doing so it carries the loop of the string 34 through the eye 550 of the tag and around the end of the tag onto the same side of the tag as that from which the 65 loop was inserted through the eye of the tag,

the string 34 being held taut during this operation by the tension devices 14. When the parts reach the position shown in Fig. 23, the loop remover 560 moves into position, enters the loop of the string 34, as seen in Fig. 70 23, and picks said loop off from the notched end of the threadder. After the loop remover 560 has entered the loop it moves into the position shown in Fig. 24, thus carrying the loop into the position shown in the perspective view of the tag in said figure, and simultaneously the threadder turns backwardly toward its initial position. It will be noted that the threadder is provided on its exterior with a string-receiving groove 57, 80 see Fig. 18, in which the string is received as it is carried through the tag. The end 58 of the threadder which has the notch 40 therein extends beyond the end of the groove 57 so that the loop of the string can be readily 85 picked off from the threadder by the loop remover 560, as will be more fully described.

During the backward movement of the threadder and while the string is held by the loop remover, said string is still frictionally 90 held by the tension members 14. While the loop is thus held a knotter 59 moves forward into the open loop, and when the threadder has returned to its initial position, as shown in Fig. 14, said knotter grasps the ends of the 95 string which have now been pulled clear through the tension devices 14 and draws said ends through the opened loop, as shown in Figs. 25 and 26, thus completing the stringing 100 operation.

It will be noted that owing to the circular shape of the threadder 39 and the fact that it oscillates about an axis extending through the center of the curve, the threadder is enabled to pass through the eye of the tag and 105 to carry the loop of the string around the edge of the tag onto that side thereof from which the string entered said eye without disturbing the position of the tag. This is plainly seen in Figs. 22 and 23, and especially in Fig. 23, for since said threadder is made on the arc of a circle and oscillates about the center of the circle as an axis, the threadder will pass through the eye of the tag from the position shown in Fig. 22 to that 110 shown in Fig. 23 without moving the tag toward or from the center of motion.

The knotter is arranged to operate in substantially the horizontal plane of the aperture 550 through the tag, as seen in Fig. 120 27, and because of the helical shape of the threadder illustrated in the drawings and above referred to, the end 40 thereof is situated above the shank 61 so as to afford sufficient clearance room for the proper operation of the knotter and the loop remover. The cam 55 has the same pitch as the helix 125 of the threadder, and as a result during the rotation of the threadder the latter is elevated so that the portion of the threadder which oc- 130

copies the eye 550 of the tag is always in the same vertical position, and the threader sort of screws or spirals into said eye. The threader is curved through an arc of more than 180° as shown so that when the threader is in the position shown in Figs. 24 and 25, the shank 61 of the threader extends underneath the knotter, but because of the helical shape of the threader the shank is sufficiently below the knotter so as not to interfere with the operation thereof. The movement of the knotter is so timed with reference to that of the threader that the knotter is in its advanced position with the jaws thereof open just at the time when the end 40 of the threader is being withdrawn from the eye 550 of the tag, and since the knotter works in the same horizontal plane as the eye of the tag it will be evident that after the threader has withdrawn from the tag, the portion of the string between the threader and the tag is in position to be grasped by the open jaws of the knotter. As stated above, the movement of the knotter is not interfered with in any way by the upper end of the post 60 or the shank 61 of the threader, because of the helical shape of the threader and its rising and falling movement due to the cam 55. It will be noted that the tag is held in such a position that the axis about which the threader turns extends parallel to the tag or, in other words, the tag while being strung is held in a plane parallel to the axis of the helical curve of the threader. The helical shape of the threader I regard as of great importance because by means of it a circular threader may be employed without interfering in any way with the operation of the loop remover and knotter.

In order that the string may feed into the string-receiving groove 57 as the threader is advanced through the tag, I will preferably place the ways 28 on a slight incline and so arrange the parts that when the member 8 is brought to rest after its turning movement the string-presenting arm 9 stands substantially parallel with said ways. The inclination of the ways and of the arm 9 is shown in dotted lines Fig. 17, and such inclination is the same as that of the helical curve on which the threader is formed, so that as the string-presenter recedes, as shown in Fig. 23, the portion of the string between said presenter and threader is on the same inclination as that of the string-receiving groove 57.

The loop-remover 560 is shown as mounted on an arm 64 which is pivoted to the frame, as at 65, and said arm has a projection 66 engaging a cam groove 67 in a cam 68 on the shaft 4, said cam groove being properly shaped to give the loop-remover its movement toward and from the threader. Said loop-remover is shown as having a forked end 69, see Fig. 20, and it is pivotally mounted upon the end of the arm 64, as at 70, and is

provided with a tail 71 which is adapted to engage a projection or arm 72 carried by the post 36 as the loop-remover swings toward the threader, said tail by engagement with the arm swinging the loop-remover away from the threader laterally, as shown in Figs. 24 and 25. A suitable spring 73 may be employed for returning the opener to its initial position as the tail 71 is carried out of contact with the projection 72 during the backward movement of the arm 64. The notch in the end 69 of the loop-remover is wide enough to receive the notched end 40 of the threader so that when the threader reaches the position shown in Fig. 23 the movement of the loop-remover toward the threader causes the notched end of the threader to enter between the two jaws 69 of the loop-remover, said jaws passing between the threader and the string, as shown in Fig. 20; so that when the loop-remover is moved laterally into the position shown in Fig. 24, the loop will be picked off from the threader. The loop-remover is provided with a tension spring 76 which by engagement with the string serves to hold the string thereon and prevent the loop from falling off therefrom.

The knotter 59 which enters the opened loop, as shown in Figs. 24 and 25, is herein shown as comprising two jaws 77 and 78. These jaws are each pivoted at 80 to an arm 81 which in turn is pivotally mounted on the stud 65, and said stud is operated by a cam groove 82 which, if desired, may be formed in the cam member 68. The two jaws 77 and 78 are normally kept closed together by a suitable spring 85, and said jaws are maintained in their closed position until they enter the opened loop, as shown in Fig. 24, at which time they are separated so that during their further forward movement they receive between them the ends of the severed string 34, as shown in Fig. 28. After the ends of the severed strings have been received between the jaws they are closed together again thereby to grip the string so that upon their backward movement they draw the ends of the string through the opened loop. For thus opening the jaws at the proper time, I have shown said jaws as extended beyond their pivotal point, as at 87, the portions 87 being separated from each other and extending to meet each other at their ends, as at 88.

Supported by the frame is a jaw-opening wedge 89 which has the beveled or thinned edge 90. This jaw-opening wedge is normally situated between the arms 87 so that as the arm 81 swings to the right, Fig. 10, to carry the knotter through the opened loop, the point 90 of the wedge 89 enters between the ends 88 of the arms 87 and thus separates them and opens the jaws of the knotter, as seen in Fig. 13. The jaws of the knotter are closed when they first enter the opened loop,

but as they get into the position shown in Figs. 13 and 24, they are opened by the wedge 89, as above described, and they continue open until the ends 88 of the arms 87 pass off from said wedge at which time the open jaws have been carried far enough to the left, Fig. 25, so that the ends of the string are received between the jaws. As soon as the ends 88 pass off from the wedge 89, the jaws automatically close thereby gripping the ends of the string, and at this time the cam groove 82 gives the knotter its backward movement, during which movement the ends of the string are drawn through the opened loop, as will be clearly seen from Fig. 26.

200 designates a positioning lug which holds the arms 87 in their proper position after they have passed off from the wedge 89. 20 Said wedge serves to position said arms at other times.

In order to avoid the opening of the jaws during the backward movement I have mounted the wedge 89 upon an arm 92 which is pivoted to a stand 93, as at 94, so that when the flanges 87 engage said wedge upon the backward movement the wedge may swing laterally out of the way to permit the flanges to pass. Said wedge is held in its normal position by any suitable means such as a spring 95. I have also shown means for automatically feeding the tags singly to the machine.

The platform or table 6 is arranged to support a plurality of tags set on edge, and I have provided means for feeding the end tag forward into the holder 7 at the proper time, and I have also provided means to discharge the tag from the holder after it has been strung. The tag-feeding device herein shown 35 comprises a feeding roll 100 mounted on a suitable shaft 101, a portion of which roll is situated in an opening 920 in the side wall of the holder 7, said roll projecting far enough into the holder to have frictional engagement 40 with the end tag. The shaft 101 is rotated intermittently, the rotation thereof occurring at the time when it is desired to feed a tag forward into the holder 7. For thus rotating the shaft I have mounted thereon a gear wheel 102 which meshes with a rack 103 carried by an arm 104 fast on a rock-shaft 105. The rock-shaft may be oscillated by a suitable cam 106 carried by the shaft 4 and operating an arm 107 secured to the rock-shaft. This would give the rack 103 a vibrating movement, and therefore I propose to interpose a pawl-and-ratchet connection 174, see Fig. 15, between the gear 102 and the shaft 101, so that upon the movement of the rack in one direction the shaft will be rotated and upon its movement in the opposite direction said shaft will remain stationary. Since the rack 103 is operated from the main shaft 4, it will follow that the feeding roll 101

will have a forward turning movement once 65 for each cycle of operations.

The roll 100 is perfectly eccentric, as seen in Fig. 14, the eccentric portion acting on the tag to feed it into place and passing off from the tag after it is in position thereby relieving 70 the pressure on the tag to permit it to be discharged.

The tags on the table 6 may be moved forward toward the holder 7 as they are fed thereto by any suitable means. As herein 75 shown the table 6 is given an inclination so that the tags will by the action of gravity feed themselves down toward the holder 7 as they are fed from the table and strung. For discharging the strung tags from the holder I have shown a pair of jaws 110, 111, see Fig. 3, which are mounted upon an arm 112 pivoted to the frame, as at 113. While these jaws may have any suitable construction I have herein shown them as made from a piece 85 of resilient metal, which is bent into substantially U-shape and one side of which is secured to the arm 112 and the other side of which is held against the first-named side by the resiliency thereof. The edges of the jaws 90 are flared outwardly slightly to form a flaring mouth which facilitates the entrance of the tag into the jaws.

After the tag has been fed into the holder and at some time during the stringing thereof, the arm 112 is swung downwardly to cause the tag to enter between the jaws 110, 111, and after the tag has been completely strung, said arm is swung upwardly, the strung tag being carried with it owing to the 100 frictional engagement of the jaws with said tag. As the arm swings upwardly the tag carried thereby will engage a suitable stop 120 which dislodges the strung tag from the jaws permitting a tag to be discharged from 105 the chute 121 into any suitable receptacle. For thus operating the arm 112 I have shown it as having rigid therewith the segmental gear 122 which meshes with and is operated by a segmental gear 123 carried by a lever 116 124 that is pivoted to the frame, as at 125. The arm 124 has a projection thereon which is received within a cam groove 126 formed in a cam member 127 carried by the main shaft 4, said cam groove being properly timed 115 to give the arm 112 its oscillating movement.

In order to adapt my machine for stringing tags of different sizes I have shown the support for the tag as being adjustable. Some tags are wider than others, and some tags have their eyes nearer the end than other tags. In order to accommodate tags of all sizes I propose to make the tag support adjustable both in the direction of the length of the tag and in the direction of the width of the tag sustained thereby.

To accommodate tags of different widths I have shown the tag support 6 as being ver-

tically adjustable on the posts 56; said tag-support is carried by a block 152 which can be adjusted vertically on the posts 56, and which is clamped to the post in any adjusted position by means of clamping screws 153. By adjusting this block 152 and the tag-support 6 vertically said tag-support may be properly positioned so that the eye of a tag of any width will be in proper position to 10 have the threader enter it.

The position of the eye of the tag horizontally with reference to the threader is determined by the positioning device 7, and in order to permit the device to string tags in 15 which the eye may be situated different distances from the end of the tag I propose to make said positioning device adjustable toward and from the threader so that by adjusting it the eye of any style of tag may be brought into proper position to receive the 20 threader. As herein shown said positioning device 7 has extending therefrom a flange 154 which rests on a bearing block 155 carried by the post 56. Said flange 154 is 25 shown as having slots 156 therein through which the clamping screws 157 pass, said screws entering the block 155. By this means the positioning device 7 may be adjusted toward and from the threader to accommodate different sizes of tags. It will 30 be understood that the positioning device is separate from the table or tag-support 6.

The adjustment of the table or tag-support 6 may be adjusted independently of the 35 adjustment of the positioning device, and similarly said positioning device may be adjusted independently of the table.

I have not attempted herein to show modifications of the invention or different embodiments thereof, and the form of the invention herein shown has been chosen merely to illustrate the principle thereof.

Having described my invention what I claim as new and desire to secure by Letters

45 Patent is:—

1. In a tag-stringing machine, the combination with means to sustain a tag, of a threader, means to move the threader to carry a loop of string through the eye of said tag and around the edge thereof, and means to draw the end of the string through said loop.

2. In a tag-stringing-machine, the combination with means to sustain a tag, of a threader having at its end a string-engaging portion, means to move the string-engaging portion of the threader through the eye of the tag and around the edge thereof thereby to loop a string through said eye and carry 55 the looped end around the edge of the tag onto that side thereof from which the loop was inserted, and means to draw the end of the string through said loop.

3. In a tag-stringing machine, the combi-

nation with means to sustain a tag, of means 65 to sustain a string at one side of the tag, a threader, having a string engaging portion and means to move the string engaging portion of the threader against the string, through the eye of said tag and around the edge thereof, to loop the string through said eye of the tag and carry the looped end around the edge of the tag onto that side thereof from which the loop was inserted.

4. In a tag-stringing machine, the combination with means to sustain a tag in a fixed position, of means to sustain a string at one side of the tag, a threader having a portion to engage said string, means to move said portion of the threader against the string, through the eye of said tag and around the edge thereof thereby to loop the string through said eye of the tag and carry the looped end around the edge of the tag onto that side thereof from which the loop was inserted, and means to draw the ends of the string through said loop.

5. In a tag-stringing machine, the combination with an oscillatory threader arranged to loop a length of string through the eye of 90 the tag, of means to draw the ends of said string through said loop.

6. In a tag-stringing machine, the combination with a curved threader arranged to loop a length of string through the eye of the 95 tag, of means to draw the ends of the string through said loop.

7. In a tag-stringing machine, the combination with a curved oscillatory threader arranged to loop a length of string through the 100 eye of a tag, of means to draw the ends of the string through said loop.

8. In a tag-stringing machine, the combination with a helically-shaped threader to loop a length of string through the eye of a 105 tag, of means to draw the ends of the string through the loop.

9. In a tag-stringing machine, the combination with an oscillatory threader having a helical shape of means to cause said threader 110 to loop a length of string through the eye of a tag, and means to draw the ends of the string through the loop thereof.

10. In a tag-stringing machine, the combination with an oscillatory threader having a helical shape of means to cause said threader 115 to loop a length of string through the eye of a tag and to carry the looped ends around the end of the tag, and means to draw the end of the string through the loop.

11. In a tag-stringing machine, the combination with an oscillatory helically-shaped threader arranged to loop the end of the string through the eye of the tag, and to carry the looped end around the end of said 125 tag, of a loop-remover to take the loop from the threader, and a knotter to draw the ends of the string through said loop.

12. In a tag-stringing machine, the combination with an oscillatory helically-shaped threader arranged to loop a length of string through the eye of a tag and to carry the looped end around the end of the tag, of a loop-remover to take the loop from the threader, a knotter, and means to advance the knotter into engagement with the ends of the string while the threader is being withdrawn from the tag and to withdraw the knotter from the loop, thereby drawing the ends of the string therethrough after the threader has returned to its initial position.
13. In a tag-stringing machine, the combination with an oscillatory helically-shaped threader, of means to oscillate said threader about an axis passing through the center of the helical curve thereof, thereby to pass a string through the eye of a tag, means to move the threader longitudinally of said axis as it turns and a knotter to knot the string to the tag.
14. In a tag-stringing machine, the combination with an oscillatory helically-shaped threader to loop a string through an eye of a tag, of means to oscillate said threader, means to maintain the portion thereof passing through said eye at a fixed point and a knotter to draw the ends of the string through the loop thereof.
15. In a tag-stringing machine, the combination with a helically-shaped threader to loop a string through the eye of a tag, of means to oscillate said threader, and a knotter arranged to move transversely to the axis of motion of the threader.
16. In a tag-stringing machine, the combination with a helically-shaped threader to loop a string through the eye of a tag, of means to oscillate said threader, a knotter, and means to move the knotter forwardly through the loop of string and in a direction transverse to the axis of oscillation of the threader while the threader is being retracted, and means to retract said knotter thereby to withdraw the end of the string through the loop thereof.
17. In a tag-stringing machine, the combination with a threader to insert a string through the eye of a tag, of a rotary string-presenting device having means to engage the end of the string, and mechanism to rotate said device to present the string to the threader.
18. In a tag-stringing machine, the combination with a threader to loop a length of string through the eye of a tag, of a rotary string-presenting device having means to engage the end of the string, and devices to rotate said device to present the central portion of the length of string to the threader.
19. In a tag-stringing machine, a threader to insert a string in a tag, of a rotary string-presenting device having means to engage both ends of a length of string and means to rotate said device to present said length of string to said threader.
20. In a tag-stringing machine, the combination with a threader to loop a string through the eye of a tag, of means to feed positively both ends of a length of string to present the central portion of said length to the threader and means to draw the ends of said string through the loop thereof.
21. In a tag-stringing machine, the combination with a threader to insert a string in a tag, of rotary means to feed positively both ends of a length of string to said threader, and means to sever said length.
22. In a tag-stringing machine, the combination with a threader to loop a string through the eye of a tag, of a rotary string-presenting device having means to engage both ends of a length of string means to rotate said device to present the central portion of said length to the threader, and means to sever said length.
23. In a tag-stringing machine, the combination with a threader to insert a string through the eye of a tag, of a rotary string-presenting device having means to engage a length of string at a plurality of points and means to rotate said device thereby to present said string to said threader.
24. In a tag-stringing machine, the combination with a threader to loop a string through the eye of a tag, of movable means to engage a length of string at a plurality of points and present the central portion of said length to the threader.
25. In a tag-stringing machine, the combination with a threader to loop a string through the eye of a tag, of movable means to engage a length of string at a plurality of points and present the central portion of said length to the threader, and a device to sever said length of string from the source of supply.
26. In a tag-stringing machine, the combination with a threader to loop a string through the eye of a tag, of movable means to engage a length of string at a plurality of points and present the central portion of said length to the threader, and a device to sever said length of string from a source of supply after said length has been presented to the threader.
27. In a tag-stringing machine, the combination with a threader to loop a string through the eye of a tag, of movable means to engage a length of string at a plurality of points and to present the central portion of said length to said threader, and means to sever said length from a source of supply.
28. In a tag-stringing machine, the combination with a threader to insert a string in the eye of a tag, of means to present a length of string to said threader, and means to

maintain tension on said length of string while being inserted through said eye.

29. In a tag-stringing machine, the combination with a threader to loop the length of string through the eye of a tag, of means to present the central portion of a length of string to said threader, and means to maintain a tension on both ends of said string while it is being acted on by the threader.

10 30. In a tag-stringing machine, the combination with string-presenting mechanism having separated string-carrying fingers, of a threader to engage said string between the fingers and loop said string through the eye 15 of a tag, and means to maintain the string on both sides of the threader under tension while it is acted on by said threader.

31. In a tag-stringing machine, the combination with string-presenting mechanism 20 having separated string-carrying fingers, of a threader to engage said string between the fingers and loop, said string through the eye of a tag, a tension device associated with each finger and means to draw the ends of said 25 string through the loop thereof.

32. In a tag-stringing machine, the combination with string-presenting mechanism having separated string-carrying fingers, of an oscillating threader to engage said string 30 between said fingers and loop the string through the eye of a tag, and means to maintain the string on both sides of the threader under tension while it is acted on by said threader.

35 33. In a tag-stringing machine, the combination with a threader to insert a string through the eye of a tag, of rotary string-presenting mechanism having means to control a length of string throughout its entire 40 extent, and means to rotate said mechanism thereby to present said string to the threader.

34. In a tag-stringing machine, the combination with a threader arranged to loop a string through the eye of a tag, of string-presenting mechanism having means to control the length of string throughout its entire extent and present the central portion of the string to the threader and means to draw the ends of said string through the loop thereof.

50 35. In a tag-stringing machine, the combination with a threader to insert a rotary string through the eye of a tag, of string-presenting mechanism and means to rotate said mechanism thereby to present a string to the threader, said mechanism having means to control the string throughout its entire length while being presented and to maintain said string under tension while it is acted on by the threader.

60 36. In a tag-stringing machine, the combination with a threader to loop a string through the eye of a tag, of string-presenting mechanism to present the central portion of a length of string to said threader, said mechanism having means to control said length of

string throughout its entire length while being presented, and tension devices to act on both sides of the central portion of said length while the string is being threaded through the eye of the tag.

70 37. In a tag-stringing machine, the combination with a threader, of a string-presenting mechanism comprising a rotary member having a plurality of radial arms, and means to rotate said member to present the lengths of string between said arms successively to the threader.

75 38. In a tag-stringing machine, the combination with a threader, of string-presenting mechanism comprising a rotary member having a plurality of arms, each having string-engaging means at its outer end, and means to rotate said member to present the lengths of string between said arms successively to the threader.

80 39. In a tag-stringing machine, the combination with a threader, of string-presenting mechanism comprising a rotary member having a plurality of arms, each having string-engaging means at its outer end, and means to rotate said member to place the lengths of string between each arm successively into position to be presented to the threader, and means to move said member toward and from the threader.

85 40. In a tag-stringing device, the combination with a threader, of string-presenting mechanism comprising a rotary member having a plurality of radially arranged arms, the alternate arms having tension devices to engage the string and the other arms having gripping devices, and means to rotate said member intermittently to present different lengths of string carried thereby to the threader.

90 41. In a tag-stringing device, the combination with a threader, of string-presenting mechanism comprising a rotary member having a plurality of radially arranged arms, the alternate arms having tension devices to engage the string and the other arms having gripping devices, and means to move said member toward and from the threader thereby to present different lengths of string carried thereby to the threader.

95 42. In a tag-stringing device, the combination with a threader, of string-presenting mechanism comprising a rotary member having a plurality of radially arranged arms, the alternate arms having tension devices to engage the string and the other arms having gripping devices and cutters means to rotate said member intermittently to present different lengths of string carried thereby to the threader, and means to operate the cutters.

100 43. In a tag-stringing machine, tag-stringing mechanism including a helically-shaped threader having an end to engage a string and also provided with a string-re-

- ceiving groove in its outer face, said threader having a length less than one complete turn of the helix.
44. In a tag-stringing machine, tag-stringing mechanism including a helically-shaped threader having a length less than one complete turn of the helix and also having a string-receiving groove in its outer face and a notched end.
- 10 45. In a tag-stringing machine, the combination with a curved threader having a string-receiving groove in its outer face and a notched end of means to oscillate said threader to cause the latter to loop a string 15 through the eye of a tag, and a knotter to draw the ends of the string through the loop thereof.
- 20 46. In a tag-stringing machine, the combination with a helically-grooved threader having a string-receiving groove in its outer 25 face, of string-presenting mechanism including an arm arranged tangentially to said threader.
- 25 47. In a tag-stringing machine, the combination with a helically-grooved threader having a string-receiving groove in its outer face, of string-presenting mechanism including an arm arranged tangentially to said threader and having an inclination 30 corresponding to the pitch of the helix of the threader.
- 35 48. In a tag-stringing machine, the combination with a helically-shaped threader, of a rotary member having string-presenting arms, means to rotate said member to present said arms successively to the threader.
- 40 49. In a tag-stringing machine, the combination with a helically-shaped threader, of a rotary member having a plurality of string-presenting arms, means to rotate said member to present said arms successively to the threader, each arm when thus presented standing tangentially to the threader.
- 45 50. In a tag-stringing machine, the combination with a helically-shaped threader, of a rotary member having a plurality of string-presenting arms, means to rotate said member to present said arms successively to the threader, and means to position each 50 arm when presented to the threader so that said arm stands at an inclination corresponding to the pitch of the helix of the threader.
- 55 51. In a tag-stringing machine, tag-stringing mechanism combined with a tag-holder for holding a tag while being strung, said tag holder being bodily adjustable relative to the tag-stringing mechanism.
- 60 52. In a tag-stringing machine, tag-stringing mechanism combined with a tag-holder for holding a tag while being strung, said tag holder being bodily adjustable in two directions relative to said tag-stringing mechanism.
- 65 53. In a tag-stringing machine, tag-stringing mechanism combined with a tag- holder for holding a tag while being strung, said tag holder being bodily adjustable in the direction of the length of the tag sustained thereby.
54. In a tag-stringing machine, tag-stringing mechanism combined with a tag-holder for holding a tag while being strung, said tag holder being bodily adjustable in the direction of the width of the tag.
55. In a tag-stringing machine, tag-stringing mechanism, combined with a tag-holder for holding a tag while being strung, said tag holder being bodily adjustable both in the direction of the length of the tag and in the direction of the width of the tag.
56. In a tag-stringing machine, tag-stringing mechanism in combination with means to feed tags thereto, and an oscillatory tag-removing member to remove the strung tags therefrom.
57. In a tag-stringing machine, tag-stringing mechanism in combination with means to support a stack of tags, and a feeding roll to feed the tags singly to said mechanism.
58. In a tag-stringing machine, tag-stringing mechanism in combination with means to support a stack of tags, a feeding roll to feed the tags singly to said mechanism, and a tag-remover to remove the strung tags therefrom.
59. In a tag-stringing machine, the combination with an oscillatory helically-shaped threader having a length less than one turn of a helix, of means to oscillate said threader about an axis passing through the center of the helical curve thereof, and means to move the threader longitudinally of said axis as it turns.
60. In a tag-stringing machine, the combination with means to hold the tag to be strung, of a helically-shaped threader situated with the axis of the helical curve thereof parallel to the plane occupied by the tag, and means to rotate said threader about its axis.
61. In a tag-stringing machine, the combination with a helically-shaped threader, of means to support a tag in a plane parallel to the axis of the helical curve of said threader, and means to operate the threader.
62. In a tag-stringing machine, the combination with a helically-shaped threader, of a post 60 extending from one end of the threader parallel to the axis thereof, and means connected to the post to oscillate the threader about its axis.
63. In a tag-stringing machine, the combination with an oscillatory shaft, of an arm extending therefrom, a post 60 on the arm extending parallel to the shaft, and a helically-shaped threader carried by said post.
64. In a tag-stringing machine, the combination with an oscillatory shaft, of an arm extending therefrom, a post 60 on the arm extending parallel to the shaft, and a helically-

shaped threader carried by said post, the axis of the helical curve of the threader coinciding with that of the shaft.

65. In a tag-stringing machine, the combination with means to support a tag to be strung, of a helically-shaped threader to pass a string through the eye of a tag, the axis of the helical curve of the threader extending parallel to the tag, a post 60 secured to one end of the threader and extending parallel to the axis thereof, and means connected with the post for oscillating the threader about its axis.

66. In a tag-stringing machine, the combination with means to support a tag to be strung, of a helically-shaped threader to pass

a string through the eye of a tag, the axis of the helical curve of the threader extending parallel to the tag, a post 60 secured to one end of the threader and extending parallel to the axis thereof, and means connected with the post for oscillating the threader about its axis, said post having a length greater than one-half the width of the tag.

In testimony whereof, I have signed my name to this specification, in the presence of two subscribing witnesses.

LAWRENCE A. McGRATH.
